UNITED STATES PATENT OFFICE.

WILLIAM P. NOREEN, OF WATERTOWN, MINNESOTA.

DETACHABLE BUMPER FOR BOLSTER-SPRINGS.

1,242,025.

Specification of Letters Patent.

Patented Oct. 2, 1917.

Application filed May 22, 1916. Serial No. 99,076.

To all whom it may concern:

Be it known that I, WILLIAM P. NOREEN, a citizen of the United States, residing at Watertown, in the county of Carver and 5 State of Minnesota, have invented a new and useful Improvement in Detachable Bumpers for Bolster-Springs, of which the following is a specification.

This invention relates to certain new and 10 useful improvements in vehicle springs and has more especial reference to means for protecting such springs against damage occasioned by excessive loads carried within the vehicle or by sudden jars, as where the 15 wheels of the vehicle pass over an irregularity in the road being traveled.

An object of the invention is to provide a device for this purpose, which is simple, efficient and of economical construction and 20 which may be easily and quickly positioned upon the bolster or other portion of the wagon frame to relieve the wagon springs under certain conditions.

Other and further objects and advantages 25 of the invention will be hereinafter set forth and the novel features thereof defined by the appended claims.

In the drawings:

Figure 1 is a front elevation of a wagon 30 bolster having a spring attachment thereon, and with which my invention is shown applied;

Fig. 2 is a similar view of the bolster supporting my invention, and representing 35 the springs in an assumed position under load;

Fig. 3 is a detail perspective view of my invention detached; and

Fig. 4 is a section taken on the line X—X 40 of Fig. 1.

Like numerals of reference refer to like parts in the several figures of the drawing.

In the drawings, the reference character A represents one of the bolsters of a wagon 45 at the opposite ends of which are disposed suitable side posts or standards B.

Loosely straddling the bolster adjacent each of the standards is a U-shaped stirrup C, the respective ends of each of which are 50 secured to the ends of springs D on either side of the bolster, as clearly shown. At their central portions, the springs are attached by means of a plurality of U-shaped keepers E and nuts F to a frame comprising a pair of transverse bars G connected together at their ends by means of plates H

of any desired material, the outer edges of the plates lying in close proximity to the inner faces of the standards by which their movement laterally of the wagon is limited. 60

By loosely mounting the stirrups C upon the bolster, it will be appreciated that when the springs are flattened as by a weight carried within the wagon body or by a sudden jolt, the stirrups tend to ride on the surface 65 of the bolster and thus increase the resiliency and throw of the springs.

Detachably supported upon the upper surface of the bolster A, is an elongated beam in the nature of an insert J which is 70 divided at J² into two sections a and b hinged together at their adjacent ends as shown at K in Fig. 3, the remote ends of said sections being bifurcated or forked as at L, so as to straddle the inward edges of 75 the standards whereby the beam or insert is held in position.

Should at any time it be desired to place a load of such weight in or on the wagon body as would force the springs downwardly to an 80 extent which would endanger and render them liable to be broken, the beam insert J may be arranged on the bolster and prevent the descent of the load above beyond or lower than the plane assumed by the 85 upper surface of such insert. It will therefore be seen that my improved device, while in no wise normally interfering with the desired resiliency of the wagon springs affords means for protecting and consequently 90 prolonging the life of the springs used upon the wagon.

The main object of making the member J with a joint at the middle is to be able to insert said bar with its ends underneath the 95 plates H while the joint is bent without removing the frame G and the springs D secured thereto; and likewise by bending the bar J upward at the middle it may be removed upward through the frame G and 100 even through a skeleton hayrack (not shown) which usually rests with its side rails upon the plates H. If such rack in some cases may not be open enough for the upward and downward passage of the bar 105 J in bent position, one end of the rack at a time may readily be raised sufficiently to insert the bar between it and the frame G and then downward or upward through the frame. Besides the general advantage of 110 the joint that it makes the bar J easily removable when its use is for a considerable

time not required, the joint also enables the bar to be easily inserted and applied upon bolsters already manufactured or in use.

When the bar J is applied to the front 5 bolster of a vehicle it also serves to prevent upward displacement of the king-bolt J¹, as shown in Fig. 1.

In accordance with the patent statutes I have described the principles of operation 10 of my invention, together with the apparatus which I now consider to represent the best embodiment thereof, but I desire to have it understood that the construction shown is only illustrative, and that the invention 15 can be carried out by other means and applied to uses other than those above set forth within the scope of the following claims.

Having described my invention, what 20 I claim as new and desire to protect by Letters Patent is—

1. The combination with a bolster having standards at its opposite ends, of springs arranged at the sides of said bolster, stirrups connecting the ends of said springs and suspending them from the bolster, a frame carried by said springs, and means detachably mounted on said bolster and engaged with said standards for limiting the downward movement of said frame.

2. The combination with a bolster having standards at its opposite ends, of springs arranged at the sides of said bolster, stir-

rups connecting the ends of said springs and suspending them from the bolster, a 35 frame carried by said springs, and means loosely mounted on said bolster and detachably connected with said standards for limiting the downward movement of said frame.

3. The combination with a bolster having standards at its opposite ends, of springs arranged at the sides of said bolster, stirrups connecting the ends of said springs and suspending them from the bolster, a 45 frame carried by said springs, and a beam loosely mounted on said bolster and detachably connected with said standards for limiting the downward movement of said frame.

4. The combination with a bolster having standards at its opposite ends, of springs arranged at the sides of the bolster, stirrups connecting the ends of said springs and suspending them from the bolster, a 55 skeleton frame carried by said springs, and a bar adapted to rest loosely upon the bolster and limit the downward movement of the frame, said bar having its ends bifurcated so as to engage the standards, and its 60 middle portion provided with a joint to enable the bar to be passed downward and upward through the skeleton frame.

In testimony whereof, I have signed my name to this specification.

WILLIAM P. NOREEN.
